UNITED STATES PATENT OFFICE.

WILLIAM P. CRARY, OF NEW YORK, N. Y.

DESIGN FOR A LAMP-BRACKET MEMBER.

SPECIFICATION forming part of Design No. 33,191, dated September 11, 1900.

Application filed January 11, 1900. Serial No. 1,146. Term of patent 3½ years.

To all whom it may concern:

Be it known that I, WILLIAM P. CRARY, a citizen of the United States, residing in the city of New York, borough of Manhattan, in the county and State of New York, have invented and produced a certain new and original Design for a Lamp-Bracket Member, of which the following is a full, clear, and exact description, reference being had to the accompanying drawing, showing a perspective view of the bracket member.

The leading feature of my design is the vertical standards, carrying a rearwardly-extending semicircular member at their upper ends and a semicircular yoke extending forwardly from their lower ends.

Referring to the drawing, A A are the

standards, joined at the upper ends to arms B' B' on the semicircular member B and at the lower ends to the semicircular yoke C, 20 having the forward extension C', the end of which is rounded and is provided with the notch c and radial depressions c', as shown.

I claim—

The design for a lamp-bracket member, 25 herein shown and described.

In testimony that I claim the design above set forth I affix my signature in the presence of two witnesses.

WILLIAM P. CRARY.

Witnesses:

CHARLES R. SEARLE,
P. E. COLLINS.
